UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

WEB-PRINTING PRESS.

Original application filed February 7, 1912, Patent No. 1,327,580, dated January 6, 1920. Divided and this application filed November 5, 1917, Serial No. 200,313. Renewed March 20, 1924.

To all whom it may concern:

Be it known that I, HENRY A. WISE Wood, a citizen of the United States, residing at New York, in the county of New York and State of New York, have invented a new and useful Web-Printing Press, of which the following is a specification.

This is a division of my Patent No. 1,327,580, patented Jan. 6, 1920, on a printing press.

This invention relates chiefly to web presses suitable for newspaper work. The principal objects of the invention are to increase the speed, prevent stops, and improve the quality of the product of such mechanism.

Other objects of the invention are to provide simple paper handling devices of such a character that the slapping of the paper against the printing cylinder will be avoided and it will not stick to the plates; to provide for reducing the error in feeding due to the usual variation in diameter of impression cylinder; to provide means whereby the paper is less liable to break than is the case in machines now on the market, so that less expensive paper can be used; to provide a construction in which twice during each revolution the paper will be free of any impression and at liberty to move a little forward or backward to compensate for the variation in thickness of the blankets, so as to prevent the forwarding of too much paper to the folder when the blankets are fat, and too little when they are lean. Another object of the invention is to provide for positively driving all paper propelling rolls before and after printing and to provide means for preventing the paper from adhering to the inked printing plates in case of a paper break, and following them around into the inking rolls, thus avoiding the present great delays which result from the winding up of the paper on the inking rolls and the necessity of taking the rolls out and picking off the paper before starting again. Further objects and advantages of the invention will appear hereinafter.

Reference is to be had to the accompanying drawings, in which

Fig. 1 is a diagrammatic view of a four-

deck rotary printing press constructed in accordance with this invention and showing the parts in longitudinal section;

Fig. 2 is a sectional view of a portion of one of the decks on enlarged scale showing the guide fingers;

Fig. 3 is a sectional view showing one of the guide fingers;

Fig. 4 is a side view of a portion of the device on enlarged scale;

Fig. 5 is a side elevation on enlarged scale showing a portion of the web guiding device;

Fig. 6 is an end elevation of the elements shown in Fig. 5;

Fig. 7 is a view similar to Fig. 5 showing another portion of the web guiding device;

Fig. 8 is an end elevation of the elements shown in Fig. 7;

Fig. 9 is a longitudinal sectional view on the line 9—9 of Fig. 5 showing the bearings for one of the shafts, and

Fig. 10 is a similar view on the line 10—10 of Fig. 7.

In the form of the invention shown in the drawings, a main frame 26 is provided for supporting all the mechanism herein-after described. This frame is provided with a plurality of rails 27 arranged in pairs, one of those of each pair being at a slight elevation above the other. Each rail supports a carriage or frame 28 movable therealong on rollers 29 toward and from the center of the machine. Each pair of these frames and associated elements constitutes a deck of the press.

Mounted in bearings on the lower part of this frame 26 is a driving shaft 30 having a gear 31 thereon. Through gears 32 and 33 this drives the impression cylinder shaft 34 on which the gear 33 is mounted. This gear 33 meshes with a gear 35 fixed to an impression cylinder shaft 36, located above the shaft 34 and parallel with it. Arranged preferably in vertical alignment above these shafts is a series of shafts designated 34^a, 36^a, 34^b, 36^b, 34^c, 36^c, one pair being located in each deck. On these shafts are mounted gears for driving them in a corresponding order designated 33^a, 35^a, 33^b, 35^b, 33^c and 35^c.

These gears are of the same diameter and mesh together so that all of these shafts are driven at the same speed, the lower ones of each pair in the same direction and the upper ones of each pair in the opposite direction. To perform a complete printing operation on the web, as will be obvious, each of these shafts is provided with an impression cylinder as 37, 38, 37^a, 38^a, 37^b, 10 38^b, 37^c, and 38^c.

On each of the shafts 34, 36, etc. there is a gear (not shown) meshing with a gear fixed on a printing cylinder shaft 41. On each of these shafts 41 is mounted a printing plate cylinder designated as 42 on the right hand side of the lower deck and 43 on the left hand side. Other plate cylinders 42^a, 43^a, 42^b, 43^b, 42^c, 43^c, appear in corresponding order in the other decks. 20 The parts just above described are supported on the main frame 26. A series of webs W—W^a, W^b—W^c, are drawn between these printing couples to be printed on both sides as will be explained more in detail herein-after. 25 On each of the shafts 41 there is located a gear 44 operating a train of gears for driving the inking mechanism I, including the form rolls 68. The details of these gears need not be gone into as any ordinary arrangement can be employed. It is to be understood however, that the same arrangement is provided in each of the several decks, and that these parts are mounted on the movable frames 28 as will be obvious 30 from a consideration of the top deck in Fig. 1.

A pressure cylinder 210 is shown for moving the carriage. With this cylinder arrangement the attendant need only turn an air cock in order that the roller carriage 28 may be moved away and back. It is sometimes desirable to move it by hand however. For this reason a rack 21 is shown fixed on the rail 27 and the carriage is shown as provided with a shaft 212 having a pinion thereon meshing with the rack. This can be used in emergencies and whenever it is not desired to use the cylinder. 40

For the purpose of locking the movable carriage 28 to rail 27, a yoke 214 is mounted on the stationary rail 27 to receive a pin 215 on the carriage and stop it. In order to lock the carriage in its operative position it is provided with a projection 216 adapted to enter a slot 217 in the stationary frame. In this projection is a shaft 218 having a square end and carrying a pinion 219 meshing with a vertical rack 220 which has a pin 221 on the end for entering a hole 222 in the stationary frame and holding the movable carriage in fixed position. 50

The paper forwarding roll 230 between the press and folder is of half the diameter of the printing cylinder. In this way it 60 has a circumference exactly the length of

one sheet and so will receive the set off of each sheet in exactly the same spot. In view of the fact that it is now almost universally the custom to have the two following plates in each plate cylinder alike it will 70 be seen that the set-off of one sheet will be returned to the next sheet in register and therefore will be off-set upon the printed portions and not upon the white spaces as has been the case heretofore. In other words 75 the off-set is registered and is therefore hidden. This is carried out in the case of each roll between the press and folder. This forwarding roll 230 as well as the forward roll 231 is driven positively from 80 the gear 44 by means of gearing 232 and 233. In this way the rolls cannot get out of register and the web is positively driven.

In order to further facilitate the positive driving of the web the following mechanism 85 is provided. On the frame is located a fixed rod 234 on which are fixed a pair of ears 235. These ears carry a rod 236 through which passes an adjusting screw 237 for engaging a lever or arm 238 loose on the rod 234 and for adjusting it about the rod. On a stud 239 on this arm is journaled a flanged pulley 240. This pulley is provided with ball bearings. Over this pulley passes an endless rubber belt 242 which also passes over 90 a flanged pulley 243 on a shaft 244. The belt holds the web firmly against the forwarding wall 231. This shaft 244 is positively driven from the gear on the roll 231 95 by a gear 245 and is mounted in ball bearings 246 on the frame. 100

On the other side of the impression mechanism the roll 230 is located as has been stated. This is made up of a plurality 105 of pulleys or cylinders fast on a shaft 249. Between any two of these cylinders a rotary slitting knife 250 can be located. The web is held against the surface of this roll by a plurality of hollow rolls 251 in which rubber rolls 253 are mounted. These rolls 251 are driven by frictional contact with the roll 230. Each of these rolls 251 is mounted on an arm 255 adjustable about a shaft 256 by a screw 257 in the same manner as described in connection with the pulley 240 and they hold the web against the forwarding roll 230. 110

Particular attention is directed to the relative locations of the rolls 230 and 231 with respect to the impression and printing cylinders. They are so located that the paper has only a slight bend about the impression cylinders, that is, each pathway is deflected from a straight line only to the extent that 115 will prevent the paper contacting with the printing plates until just after it has contacted with the impression cylinders. This is for the purpose of avoiding the slapping of the paper against the printing cylinder 120 and sticking to the plates thereof on the one 125 and sticking to the plates thereof on the one 130

hand, and to avoid wrapping the paper around the impression cylinders on the other hand, which is ordinarily done.

I bend the web pathway from a straight line only sufficiently to keep it off the type until the moment of printing, and to strip it from the type immediately after printing. In other words I permit the impression and printing cylinders to do the work of printing in a cleanly manner, but I do not permit the impression cylinder to take charge of the web to any great extent, and thus I leave the web free to go or come during the passage of the margins.

15. The objections to the usual practice are that when the blankets are too thick the cylinder will be over-diameter and the web will be fed too fast, and when the blankets are old and thin the paper is fed too slowly.

20. When the web is wrapped around a cylinder it must conform to its surface speed whether it be too fast or too slow. This brings strains into the paper and causes it to tear, unless a relatively high grade of paper is

25. used. By avoiding this wrapping, the paper is neither advanced nor retarded to as great a degree as heretofore, and fewer breaks will happen, thus permitting the use of less expensive paper and avoiding the loss of valuable time.

30. Moreover the margins of a blanket which lie between the page surfaces invariably stand up above these surfaces, and if the web is wrapped around the cylinder these, by their abnormal height, cause 35. wrinkling of the web which sets up strains that result in breaks. This danger is also substantially eliminated by this plan.

35. The web pathway between two of the points of impression is equal in length to a printed product or a multiple thereof, and the plate margins transverse of the web coincide so that those of both couples simultaneously pass their respective points of impression. Twice in each revolution therefore the 40. paper will be free of any impression and at liberty to move relatively a little forward or backward notwithstanding the blankets are too thick or too thin. This prevents the forwarding of too much paper or too little, a 45. result that could not be obtained with the usual wrap around the impression cylinder, and margins that do not coincide.

50. The plate cylinders are shielded by shields 260 at a point just beyond the points of impression. These are so arranged that the web as it leaves the line of impression passes between the shields and impression cylinders. These shields are provided with adjustable fingers 261 which protrude into the 55. margins between the plates beneath the printing line. The object of this construction is to prevent the paper from adhering to the inked plates and following them around the cylinders into the rolls in the 60. case of a paper break. This avoids the

present great delays which result from the winding up of the paper on the inking rolls and the necessity for taking the rolls out and picking off the paper before starting again. This is an important feature of the 70 invention.

75. Although I have illustrated and described a preferred embodiment of the invention described herein, I am aware of the fact that many modifications can be made therein by any person skilled in the art without departing from the scope of the invention as expressed in the claims. Therefore I do not wish to be limited to all the details of construction herein shown and described, but 80 what I do claim is:—

1. In a perfecting printing press, the combination of two printing couples each comprising an impression and a printing cylinder having the plate margins of the printing plates in position to simultaneously pass their respective points of impression, whereby twice in every revolution the web will be free of any impression and at liberty to move longitudinally, said perfecting printing couples being so located that the web passes directly from contact with one impression cylinder to contact with the next impression cylinder in a straight line without deviation therefrom. 95

95. 2. A rotary printing press containing two printing couples adapted to cooperate to perfect a web, having printing plates so positioned that the transverse margins of both printing couples will simultaneously pass 100 their respective points of impression, and a substantially straight web pathway intermediate of the two points of impression equal in length to a printed product or to a multiple thereof, so that the web will be 105 momentarily free to move longitudinally, when said margins pass their points of impression.

3. In a printing press, the combination with the printing mechanism, of a forwarding roll made up of a shaft and a plurality of cylinders mounted on said shaft, and having spaces between them for receiving slitting knives, and a roller having a yielding surface adapted to engage the web on 110 the surfaces of two of said cylinders on both sides of one of said spaces.

4. In a printing press, the combination with a printing couple, of a forwarding roll made up of a shaft and a plurality of cylinders mounted on said shaft and separated slightly to leave spaces for receiving slitting knives, and a roller having a yielding surface engaging the web on the surface of said roll closely adjacent to the edge of one of 115 said cylinders and to the space between them and the next one.

5. In a printing press, the combination with the impression mechanism, of a forwarding roll in position to receive the web 120 125 130

- directly therefrom, and a roller pressed against the surface thereof having a plurality of small rubber rolls around its circumference.
6. In a printing press, the combination with the impression mechanism, of a forwarding roll in position to feed the web directly thereto made up of a shaft and a plurality of cylinders mounted on said shaft.
7. In a perfecting web press, the combination of two printing couples having semi-cylindrical printing plates on their printing cylinders arranged so that one follows the other arranged to have their plate margins pass their respective points of impression simultaneously so that at the instant when the plate margins pass their points of impression the web will be free of pressure at said points and at liberty to be moved a little longitudinally, with a substantially straight web pathway between said points.
8. In a perfecting web press, the combination of two printing couples having semi-cylindrical printing plates on their printing cylinders arranged so that one follows the other arranged to have the two plate margins on each printing cylinder pass their respective points of impression simultaneously twice during each revolution so that at the instant when the plate margins pass their points of impression the web will be free of pressure at said points and at liberty to be moved a little longitudinally, the web pathway extending from one of said points to the other being free from contact with driven rolls or surfaces.

In testimony whereof I have hereunto affixed my signature.

HENRY A. WISE WOOD.
